(57) **CLAIM**

The ornamental design for a belt for carrying beverage bottles, as shown and described.

DESCRIPTION

FIG. 1 is a perspective view of a belt for carrying beverage bottles showing my new design, with one of the bottles removed therefrom;

FIG. 2 is a front elevational view thereof;

FIG. 3 is a rear elevational view thereof;

FIG. 4 is a top plan view thereof;

FIG. 5 is a bottom plan view thereof;

FIG. 6 is a side elevational view thereof;

FIG. 7 is an elevational view of the opposite side thereof;

FIG. 8 is a perspective view of a modified form of my design, with one of the bottles removed therefrom;

FIG. 9 is a front elevational view thereof;

FIG. 10 is a rear elevational view thereof;

FIG. 11 is a top plan view thereof;

FIG. 12 is a bottom plan view thereof;

FIG. 13 is a side elevational view thereof;

FIG. 14 is an elevational view of the opposite side thereof;

FIG. 15 is a perspective view of another embodiment of my design, showing one bottle in removed position;

FIG. 16 is a front elevational view thereof;

FIG. 17 is a rear elevational view thereof;

FIG. 18 is a top plan view thereof;

FIG. 19 is a bottom plan view thereof;

FIG. 20 is a side elevational view thereof; and,

FIG. 21 is an elevational view of the opposite side thereof.

The portions shown in broken lines in FIGS. 1, 8 and 15 are for information only and form no part of the claimed design.
